LEWIS M. HULL, OF BOONTON, NEW JERSEY, ASSIGNOR TO RADIO FREQUENCY LABORATORIES INCORPORATED, OF BOONTON, NEW JERSEY, A CORPORATION OF NEW JERSEY.

ELECTRICAL AMPLIFIER CIRCUIT.

Application filed July 20, 1927. Serial No. 207,239.

This invention relates to electrical amplifier circuits of the type employing a vacuum tube including an emitting cathode, an anode, and one or more additional elements or grids. It relates especially to a balanced amplifier circuit of that type, and provides means for reducing or eliminating retroaction from the output circuit of the amplifier stage to the input circuit thereof. Such retroaction may be caused by coupling due to 10 capacities between the elements of the vacuum tube and their associated connections, and especially by coupling due to the capacity between the anode and control element, 15 or grid, of the vacuum tube.

Referring now to the drawings Fig. 1 shows a single amplifier stage embodying my invention. A three-electrode vacuum tube of standard type is employed in this particular example. Fig. 2 shows a specific example of the application of my invention to a four-electrode or double-grid type of electron tube. Fig. 3 shows a modification of the circuit of Fig. 1. Fig. 4 shows a cascaded arrangement embodying the circuit of Fig. 1.

The input circuit of the amplifier stage may assume any desired form. Referring to the arrangement shown in Fig. 1, the input circuit is connected between the control grid, G, and cathode, F, of the vacuum tube. The input circuit is here illustrated as a tuned one, including coil L_0 and variable condenser C_0 . A plate coil, L_1 , is connected 30 between anode and cathode, and any suitable source of space current, as a B-battery or socket power device may be included in circuit therewith. Coupled to the coil L_1 with mutual inductance M_{12} , is a coil L_2 . These coils have negative coupling, that is, 40 one coil is wound or connected in reverse sense as regards the other, so that if the coils were connected in series the coupling between them would produce voltages at 45 their unconnected ends which would be approximately opposite in phase. While it is possible to employ substantially unity coupling between coils L_1 and L_2 , it is not necessary to do so, and I prefer to employ 50 substantially less than unity coupling, and so avoid the high losses which are apt to take place in practice in the case of substantially unity coupling between reversed coils. In series with the coil L_2 are connected the

coil L_3 and the tuning condenser C_2 . The 55 coil L_3 is preferably not coupled to either the coil L_1 or the coil L_2 , the coupling between the coil L_3 and the coils L_1 and L_2 being in any case negligible. A balancing condenser, C_1 , may be connected between 60 the grid G and a point, X, between coils L_2 and L_3 , and serves to improve the action of the circuit. The cathode, F, is connected to a point between coil L_3 and tuning condenser C_2 , and since the cathode may be grounded, 65 the tuning condenser C_2 may also be grounded. This may be of advantage in the case of multistage amplifiers employing ganged condensers.

The approximate balance condition for 70 this circuit may be expressed:

$$\frac{M_{12}}{L_3} = \frac{C_1}{C_m}$$

where C_m represents the natural capacity between grid G and anode P, as shown by the dotted lines.

As an example, merely, of values which I have found to give a good balance and high amplification over a considerable range of 80 frequencies, I may give the following:—

$$L_1 = 18 \mu h$$

$$L_2 = 206 \mu h$$

$$L_3 = 14.5 \mu h$$

Coupling coefficient $M_{12} = 45\%$ (about)

$$\sqrt{L_1 L_2}$$

$$C_1 = 19 \mu \mu f \text{ (about)}$$

These figures are only one illustration of values which I have employed successfully. 90

Figure 2 shows my invention applied to a tube of the double-grid type. The circuit is arranged similarly to that shown in Fig. 1, in general. The second grid, G_2 , may be connected to the point X, as regards alternating current, and may also be given a constant direct current bias, as shown, if desired, by means of the battery D or otherwise. If the battery D is employed, a stoppage condenser C_3 should also be employed, 95 so as to prevent the potential of the battery D from being impressed between the cathode and control grid of the succeeding vacuum tube in a cascaded arrangement. The capacity between grids G_1 and G_2 may be employed for balancing the circuit, if the tube and coils are properly proportioned. It may be advisable, however, under some condi-

tions, to connect the additional capacity C_1 between the grids G_1 and G_2 , in order to augment the natural capacity.

Figure 3 shows a modification of the circuit of Figure 1, which may be useful in special cases. I have found that the balance of the circuit shown in Figure 1 may not be sufficiently independent of frequency in all cases, for example, if a very wide range of frequencies is to be received, or extremely accurate adjustments are intended. For such cases, the arrangement of Figure 3 tends to make the balance complete. The coil L_4 is connected in series with the coil L_1 , and is coupled to the coil L_5 , in series with the balancing capacity C_1 . L_4 should be relatively small, and L_5 somewhat larger than L_4 , so that the mutual inductance M_{45} will have about the same value as the self-inductance L_1 . The object of this arrangement is to introduce into the balancing voltage impressed upon the grid G through the condenser C_1 a small quadrature component, to compensate for the slight quadrature component introduced into the plate voltage by the flow of plate current through the coil L_1 . An exact opposition in phase between the two opposing voltages may thus be obtained. It is obvious that this arrangement is equally applicable to a double-grid type of tube.

Figure 4 shows a cascaded arrangement employing the circuit of Fig. 1. The grid and cathode of the second vacuum tube may be connected directly across the tuning condenser C_2 , as shown, or other methods of cascading the stages may be employed if preferred. It is of course understood that common B-batteries or socket power devices may be used, separate batteries being here shown for simplicity.

It is obvious that many variations and modifications of the circuits herein described fall within the scope of my invention.

45 I claim:

1. An electrical amplifier stage comprising, in combination, a vacuum tube including an anode, a cathode, a control grid, and a second grid, an input circuit for said amplifier stage, a plate coil connected between said anode and cathode, a second coil coupled to said plate coil in the reverse sense, a third coil connected in series with said second coil, a connection between said cathode and said third coil, and a connection between said second grid and a point intermediate said second and third coils.

2. An electrical amplifier stage comprising, in combination, a vacuum tube including an anode, a cathode, a control grid, and a second grid, an input circuit for said amplifier stage, a plate coil connected between said anode and cathode, a second coil coupled to said plate coil in the reverse sense, a third coil connected in series with said

second coil, a connection between said cathode and said third coil, a balancing capacity connected between said control grid and second grid, and a connection between said second grid and a point intermediate said second and third coils. 70

3. An electrical amplifier stage comprising, in combination, a vacuum tube including at least an anode, a cathode, and a control grid; an input circuit for said stage connected to said control grid; an output coupling coil connected between said anode and said cathode; a second coil coupled to said output coil in the reverse sense; a third coil connected in series with said second coil but 75 having negligible electromagnetic coupling therewith; a connection between said cathode and said third coil; and a balancing capacity connected between said grid and a point between said second and third coils. 80

4. An electrical amplifier stage comprising in combination, a vacuum tube including at least an anode, a cathode, and a control grid; an input circuit for said stage connected to said control grid; an output coupling coil connected between said anode and said cathode; a tuned circuit including 90 in series a second coil coupled to said output coil, a tuning condenser, and a third coil having negligible electromagnetic coupling 95 with said output coil; and a balancing condenser connected between said control grid and the junction of said second and third coils.

5. An electrical amplifier stage including 100 a vacuum tube having at least an anode, a cathode, and a control grid; an input circuit associated with said control grid; a tuned output circuit including in series a tuning condenser having one terminal connected to said cathode, and two coils having negligible electromagnetic coupling with 105 each other, one of said coils being coupled to a coil connected between the said anode and cathode; and a capacitive impedance connected between said control grid and one of said coils, at such a point that said stage may be balanced to reduce retroactive effects due to coupling between said output and input circuits. 110

6. An anti-regenerative electric amplifier stage including a vacuum tube having at least an anode, a cathode, and a control grid; and capacitive coupling between said anode and said control grid; a coil connected in the anode circuit of said vacuum tube; a second coil coupled to said first coil; a third coil constituting with said second coil serially connected elements of a resonant output circuit; and a balancing capacity connected between said control grid and a point in said output circuit; the ratio of the capacity of said balancing condenser to said capacity between said anode and control grid being substantially equal to the ratio of the mutual in- 115 120 125 130

ductance between said second coil and said first coil to the self-inductance of said third coil.

7. An electrical amplifier stage including

- 6 a vacuum tube having an anode, a cathode, and a control grid; a tuned output circuit including two inductance coils having negligible electromagnetic coupling with each other and connected in series between the terminals of a tuning condenser, said tuning condenser having one terminal connected to said cathode; and a balancing condenser connected between said control grid and the junction of said inductance coils in said tuned output circuit.

8. A cascade amplifier comprising a plurality of stages each of which includes a vacuum tube having at least an anode, a cathode, and a control grid; a tuned output

- 20 circuit for the first of said stages including two substantially non-coupled inductances connected between the control grid and the cathode of the vacuum tube in the second of said stages and a tuning condenser connected between the control grid and cathode of the vacuum tube in the second of said stages; and a balancing condenser connected between the control grid of the vacuum tube in the first of said stages and such a point in said 30 tuned output circuit that currents flowing to said control grid of said tube in said first stage through said balancing condenser oppose retroactive currents flowing to said control grid through the grid-anode capacity of said tube.

9. A cascade electrical amplifier comprising a plurality of stages each of which includes having a vacuum tube having an anode, a cathode, and a control electrode;

- 40 a tuned output circuit including two substantially non-coupled inductances serially connected between the control grid and the cathode of the vacuum tube in the second of said stages; and a balancing condenser connected between the control grid of the vacuum tube in the first of said stages and the junction point of said two serially connected inductances in said output circuit.

10. An electrical circuit comprising, in 50 combination, an electron tube including at least an anode, a cathode, and a control means; an input circuit associated with said control means; a coil associated with said anode and cathode; a second coil coupled to said first coil in the reverse sense; a third coil having one terminal connected to said second coil but having negligible electromagnetic coupling with said second coil; a capacitive impedance between said control means and said second and third coils; and a connection between said cathode and a second terminal of said third coil; whereby said electrical circuit may be balanced to reduce effects other than those due to desired forward repeater action of said electron tube.

11. An electrical circuit comprising, in combination, an electron tube including at least an anode, a cathode, and a control means; an input circuit associated with said control means; a coil associated with said anode and cathode; a second coil coupled to said first coil in the reverse sense; a third coil having one terminal connected to said second coil but having negligible electromagnetic coupling with said second coil; a tuning condenser connected between the non-common terminals of said second and third coils; a balancing circuit including capacitive impedance, said balancing circuit being connected between said control means and the junction of said second and third coils; and a connection between said cathode and the junction of said third coil with said tuning condenser; whereby said electrical circuit may be balanced to reduce effects other than those due to desired forward repeater action of said electron tube. 70 75 80 85

12. An electrical circuit comprising, in combination, an electron tube including an anode, a cathode, a control grid, and a second grid; an input circuit associated with said control grid; a coil associated with said anode and cathode; a second coil coupled to said first coil in the reverse sense; a third coil having one terminal connected to said second coil but having negligible electromagnetic coupling with said second coil; a balancing capacity connected between said control grid and the junction of said second and third coils; a connection between said cathode and a second terminal of said third coil; and means for imparting a positive bias to the second grid of said electron tube. 90 95 100

13. An electrical circuit comprising, in combination, an electron tube including an anode, a cathode, a control grid, and a second grid; an input circuit associated with said control grid; a coil associated with said anode and cathode; a second coil coupled to said first coil in the reverse sense; a third coil having one terminal connected to said second coil but having negligible electromagnetic coupling with said second coil; a tuning condenser connected between the non-common terminal of said second and third coils; a balancing capacity connected between said control grid and the junction of said second and third coils; a connection between said cathode and the junction of said third coil and said tuning condenser; and means for imparting a positive bias to the second grid of said electron tube. 105 110 115 120

14. A multistage electrical amplifier circuit comprising, in combination, a plurality of electron tubes each including at least an anode, a cathode, and a control electrode; an input circuit associated with the cathode and control electrode of the first of said electron tubes; a coil associated with the 125 130

anode and cathode of said first tube; a second coil electromagnetically coupled to said first coil in the reverse sense and having one terminal connected to the control electrode of the second of said electron tubes; a third coil having one terminal connected to a second terminal of said second coil and a second terminal connected to the cathode of said second tube, said third coil having negligible electromagnetic coupling with said second coil; a balancing circuit including capacitive impedance, said balancing circuit being connected between said control electrode of said first tube and the

junction of said second and third coils; a tuning condenser connected between said first terminal of said second coil and said second terminal of said third coil and across the control electrode and cathode terminals of said second tube; and a connection to ground common to said cathodes of said first and second tubes and to the junction of said tuning condenser and said third coil.

In testimony whereof, I affix my signature.

LEWIS M. HULL.
